(57) **CLAIM**

The ornamental design for a novelty item—heart wand, as shown and described.

DESCRIPTION

FIG. 1 is a perspective view of a novelty item—heart wand showing the new design with the wand portion fully retracted;

FIG. 2 is front elevational view of the FIG. 1 novelty item—heart wand;

FIG. 3 is a left side view of the FIG. 1 novelty item—heart wand, the right side view being substantially identical thereto;

FIG. 4 is a bottom plan view of the FIG. 1 novelty item—heart wand;

FIG. 5 is a top plan view of the FIG. 1 novelty item—heart wand;

FIG. 6 is a front elevational view of the novelty item—heart wand, showing the wand in a fully extended position;

FIG. 7 is a front elevational view of the novelty item—heart wand, showing alternate positions of the heart element and the wand element;

FIG. 8 is a front elevational view of the novelty item—heart wand, showing alternate positions of the heart element and the wand element; and,

FIG. 9 is a front elevational view of the FIG. 1 novelty item—heart wand with the wand element in a partially extended position.
